UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SCREW-CONTACT DEVICE.

1,290,053.

Specification of Letters Patent. Patented Jan. 7, 1919.

Application filed September 10, 1915. Serial No. 49,985.

To all whom it may concern:

Be it known that I, REUBEN B. BENJAMIN, a citizen of the United States, residing at Chicago, in the county of Cook and State 5 of Illinois, have invented new and useful Improvements in Screw-Contact Devices, of which the following is a full, clear, concise, and exact description, reference being had to the accompanying drawing, forming a 10 part of this specification.

My invention relates to a screw contact device.

One of the objects of my invention is to provide an improved screw contact which 15 can be formed by stamping.

Further objects will appear from the detailed description to follow and from the appended claims.

In the drawings, in which I have shown 20 three embodiments of my invention—

Figure 1 is a side elevation of part of an attachment plug provided with my improved screw contact;

Fig. 2 is an axial section of the plug of 25 Fig. 1;

Fig. 3 is a plan view of the screw contact of Fig. 1;

Fig. 4 is a plan view of a modified form of screw contact embodying my invention;

Fig. 5 is a side elevation of Fig. 4; and

Fig. 6 is a side elevation of an attachment plug provided with still another form of screw contact.

Referring now to the drawings in detail 30 and first to Figs. 1, 2 and 3, the part of the plug shown herein comprises an insulating base 10 for supporting the electrical contacts and conductors, a threaded contact 11 resting on the upper end of the base 10, a cap or button 12 between which and the base 10 the contact 11 is clamped, a dished center contact 13 supported on the button 12 and insulated from the contact 11 by means of said button, a screw 14 extending through 40 the center contact 13 and through openings in the button 12 and base 10 for holding the parts in position and forming part of the circuit, and a conductor 15 in contact with the threaded contact 11.

The threaded contact 11 comprises a helical edge 16 for engagement with the screw threads of a receptacle, a helical dished portion 17 adjacent the edge 16, and a disk portion 17^a which is clamped between the base 50 10 and the button 12. The entering portion

of the helical edge 16 tapers off gradually as shown at 18, while the lower end of the helical edge 16 tapers off more abruptly as shown at 19. The disk portion 17^a is provided with an opening 20 through which 60 the screw 14 extends.

It will be noted that the shape of the helical edge 16 and dished portion 17 is such that a forming tool can readily be withdrawn from engagement therewith after the contact 11 has been formed by stamping.

In the modification of Figs. 4 and 5 the threaded contact comprises a disk portion 21, a semi-circular portion 22 struck downwardly from the disk portion 21, and a semi-circular portion 23 struck upwardly from the disk portion 21, the edges of these two semi-circular portions being shaped to form a helical edge or thread 24 for engagement with the thread of a receptacle. The semi-circular portions 22 and 23 may be cut away, as indicated at 25 and 26, to facilitate the engagement of the threaded contact with the threaded receptacle. The disk portion 21 is provided with an opening 27 through 70 which the screw 14 may extend. It will be noted that this contact also can be formed by stamping.

In the modification of Fig. 6 I have shown the plug provided with a contact constructed so that the plug may be connected by a partial turn of the plug with respect to the receptacle without having to screw the plug all the way in.

In this modification the threaded contact 90 28 is similar to the form shown in Figs. 1, 2 and 3, but comprises in addition a cylindrical portion 29 at the upper end of the plug which can be inserted in the receptacle without rotation of the plug. The 95 lower portion of the contact 28 is stamped to form a helical edge 30, and a helical dished portion 31 similar to the helical edge 16 and dished portion 17 of the form of Figs. 1, 2 and 3.

In this modification also the construction is such that the forming tool can be readily withdrawn from the contact 28 after the latter has been formed by stamping.

Having thus described my invention what 105 I claim as new and desire to secure by Letters Patent is:—

1. In a device of the class described, an insulating base and a threaded contact of sheet material supported by said base, said 110

2

contact having a peripheral helical edge located at substantially the crest of the thread, whereby said threads may be formed by a die moving axially with respect to said threaded contact and whereby said die may be withdrawn by axial movement without interference from said threads.

2. A threaded contact of sheet metal, said sheet metal having a peripheral helical edge located at substantially the crest of the thread whereby said threads may be formed by a die moving axially with respect to said threaded contact and whereby said die may be withdrawn by axial movement without interference from said threads.

3. A threaded contact of sheet metal, said sheet metal having a peripheral helical edge located at substantially the crest of the thread

and a dished portion adjacent said edge, whereby said threads may be formed by a die moving axially with respect to said threaded contact and whereby said die may be withdrawn by axial movement without interference from said threads.

4. A threaded contact of sheet metal, said sheet metal having a peripheral helical edge located at substantially the crest of the thread and a helical dished portion adjacent said helical edge, whereby said threads may be formed by a die moving axially with respect to said threaded contact and whereby said die may be withdrawn by axial movement without interference from said threads.

In witness whereof, I have hereunto subscribed my name.

REUBEN B. BENJAMIN.
